UNITED STATES PATENT OFFICE

WILLIAM J. BARNES, OF OSHKOSH, WISCONSIN.

LETTER-COPYING PRESS.

SPECIFICATION forming part of Letters Patent No. 392,486, dated November 6, 1888.

Application filed April 3, 1888. Serial No. 269,522. (No model.)

To all whom it may concern:

Be it known that I, WILLIAM J. BARNES, a citizen of the United States, residing at Oshkosh, in the county of Winnebago and State of Wisconsin, have invented certain new and useful Improvements in Letter-Copying Presses; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 My invention relates to improvements in letter copying presses; and the object of my improvements is to apply compound-lever power and to equalize and adjust the pressure. I attain these objects by the construction and 20 mechanism illustrated in the accompanying drawings, in which—

Figure 1 is a perspective view of the press with the lever down and power applied. Fig. 2 is a cross-sectional view through the center 25 of the press and lever. Fig. 3 is a top view of lower end of lever D and connections.

Similar letters refer to similar parts throughout the several views.

A A A is the outside box, the top B being 30 strengthened by the cross-cleats b b, bolted through the top and sides to the bottom by the bolts c c c.

e is an opening through the top to allow 35 passage of lower end of lever D.

D is a lever attached to the top at the fulcrum F by a hinge and connected at the lower end with the adjusting thumb-screw or bolt E.

f is a partition extending across the box, with an opening, i, in the center to allow 40 passage of the equalizing-lever m.

The screw-thread at lower end of bolt E passes through an opening in rear end of the lever m and screws into the nut n, the nut n being fastened movably over the opening in 45 the lever m, so as to allow the bolt E to be thrown off the center when the lever is raised. The lever m is pivotally connected to the front side of the box on its inner face at the fulcrum P, and is connected with the carrying-table t by the bolt R, which is fastened to the center of the table t and slides longitudinally

in the oblong slot r, the lever m bearing against the shoulder s.

By reason of the structure just described the carrying-table can rock on the shoulders, 55 so as to accommodate itself to any variation from a horizontal plane which may exist at the under side of the book or copying material. This feature of the apparatus is important, for the reason that the outer edges of a copying-book usually spread more than the edges which are bound, and if the two pressing-surfaces approach each other lying in parallel planes the written matter near the binding will copy much more distinctly than that near the 60 free edges. If, however, one of the pressing-surfaces can tilt slightly, so as to accommodate itself to the angle of the book-cover, all portions of the writing will be subjected to equal pressure, and a uniformity of copying will be 65 secured.

T is the extracting-ribbon to pull the letter-book from the press.

K is a catch fitting into the notch L to hold the lever down. The weight of the handle k 75 causes it to latch automatically.

The lower end of lever D is forked, as shown in Fig. 3, to admit passage of the thumb-screw E, which passes through the opening x in the iron cross-bar z, which is pivoted to the forks 80 of the lever u u. The thumb-screw or bolt-head rests upon and the bolt turns in the cross-piece z. The pivoted bearings of the cross-piece allow it to turn as the lever D is raised and lowered. By turning the thumb-screw E 85 the lever m is raised or lowered to adjust the press to letter-books of different thickness. The thumb screw E is also the connecting-rod between the two levers D and m.

In using the press, the lever D being raised, 90 I slide the letter-book into the opening o above the ribbon T and upon the table t. Then, by taking hold of the handle of the lever D, by a single downward pressure I raise the lever m, which bears upwardly against the shoulder 95 s at the center of the table t, and I thereby apply the pressure to the center of the letter-book against the top B. I have a compound-lever action. A pressure downward upon the handle of lever D causes a multiplied upward 100 pressure against the center of the table t, and this pressure can be increased by increasing

the ratio in length of the power-arm to the weight-arm of both levers.

The press, if made of hard wood, excepting the bolts, bearings, and hinges, will be strong enough to withstand pressure. The power applied being downward, it is not necessary that the press be of iron and of great weight or that it be fastened to an immovable object. It only requires a single downward pressure of to the lever D to operate the press.

Therefore what I claim as my invention, and desire to secure by Letters Patent, is—

The combination of the fixed pressure-board B, the pressure-lever m, mounted so as to rock on a fixed bearing at one end, a tilting pressure-table carried by the lever, a hand-lever, and a link connecting the same with the pressure-lever.

In testimony whereof I affix my signature in presence of two witnesses.

WILLIAM J. BARNES.
